UNITED STATES PATENT OFFICE.

GEORGE W. RHINES, OF ROCHESTER, NEW YORK.

DESIGN FOR A CLOTHES-DRIER.

SPECIFICATION forming part of Design No. 15,427, dated September 23, 1884.
Application filed August 16, 1883. Term of patent 7 years.

To all whom it may concern:

Be it known that I, GEORGE W. RHINES, of the city of Rochester, in the county of Monroe and State of New York, have invented and produced a new and original Design for the Ornamentation of Clothes-Driers; and I do hereby declare that the following is a full, clear, and exact description of the same, reference being had to the accompanying drawings, in 10 which—

Figure 1 of the drawings represents a front elevation of the device embodying my design, and Fig. 2 a plan view of the upper cap.

My invention relates to clothes-driers, and 15 has for its object the ornamentation of the device; and it consists in the design hereinafter particularly described.

In the drawings, the letter A designates the board or base piece, having at its upper end 20 the cap B and at its lower end the cap C. The letter D designates bars, which are shown to illustrate the utility of the device; but they form no part of the design.

The cap B is made polygonal in plan, comprising three full sides, *d*, and two half sides, *d'*, as shown in Fig. 2, the roof thereof composed of said sides inclining upward to an

apex, which is surmounted by an ornament, *f*. The cap has, further, two exterior surrounding beads, *a*, with a vertical skirting, *b*, between them and the upper bead *a*, intersected by slots *g*, while at the bottom there is a fringe, *c*, consisting of wedge-shaped pendants. The cap thus formed is ornamental and presents an attractive appearance.

The lower cap or receptacle, C, consists of a bowl having a top head, *h*, an ogee shaped body, *i*, and two ornamental ribs, *K K*, as shown in Fig. 1.

Having described my design, what I claim 40 is—

The within design for clothes-driers, consisting of the base A, having at its upper end the cap B of the form shown, ornamented by the fringe-pendants *c*, and at its lower end the 45 cap C of the form shown, ornamented by bead *h* and ribs *K*, as set forth.

In witness whereof I have hereunto signed my name in the presence of two subscribing witnesses.

GEO. W. RHINES.

Witnesses:

R. F. OSGOOD,
Z. L. DAVIS.
